HANDBAG OR THE LIKE

Meyer Somers, Freeport, N. Y.

Application October 2, 1956, Serial No. 43,185

Term of patent 7 years

(Cl. D87—3)

Fig. 1 is a side view of a handbag showing my new design;

Fig. 2 is a similar view thereof as it appears with the cover in raised position; and

Fig. 3 is a top plan view thereof.

The side opposite that of Figs. 1 and 2 is identical with Figs. 1 and 2.

I claim:

The ornamental design for a handbag or the like, substantially as shown and described.
